SAUSAGE CASING HANGER MEMBER

Donald J. Ernst, 524 W. Greenfield Ave.,
Milwaukee, Wis. 53204

Filed May 2, 1974, Ser. No. 466,163

Term of patent 14 years

Int. Cl. D8—08

U.S. Cl. D11—1 R

Fig. 1

FIG. 1 is a plan view of the sausage casing hanger member embodying my design and shown thereon;
FIG. 2 is a side elevational view of the sausage casing hanger member shown in FIG. 1; and

FIG. 3 is an end view of the sausage casing hanger member shown in FIG. 1.

I claim:

The ornamental design for a sausage casing hanger member, as shown and described.
